Primary Examiner — Barbara Fox*Assistant Examiner* — Lorna M Georges(74) *Attorney, Agent, or Firm* — Allen, Dyer, Doppelt + Gilchrist, PA(57) **CLAIM**

The ornamental design for an equipment enclosure as shown and described.

DESCRIPTION

FIG. 1 is a perspective view of the equipment enclosure showing the new design;

FIG. 2 is a front elevational view of the equipment enclosure of FIG. 1;

FIG. 3 is a back elevational view of the equipment enclosure of FIG. 1;

FIG. 4 is a left side elevational view of the equipment enclosure of FIG. 1;

FIG. 5 is a right side elevational view of the equipment enclosure of FIG. 1;

FIG. 6 is a top plan view of the equipment enclosure of FIG. 1; and,

FIG. 7 is a bottom plan view of the equipment enclosure of FIG. 1.

The dashed broken lines define the bounds of the claimed design and form no part thereof.

1 Claim, 7 Drawing Sheets(56)
